UNITED STATES PATENT OFFICE.

CHARLES F. LILLEY, OF TROY, PENNSYLVANIA.

INVALID BED-REST.

SPECIFICATION forming part of Letters Patent No. 340,334, dated April 20, 1886.

Application filed May 12, 1885. Serial No. 165,215. (No model.)

To all whom it may concern:

Be it known that I, CHARLES F. LILLEY, of Troy, in the county of Bradford and State of Pennsylvania, have invented certain new and 5 useful Improvements in Invalid Bed-Rests; and I do hereby declare that the following specification, taken in connection with the drawings furnished and forming a part thereof, is a clear, true, and complete description 10 of my invention.

My said improvements relate to that class of portable devices which can be applied to use on any bed or lounge for conveniently affording to invalids a variety of restful positions and otherwise contributing to their comfort, as well as to the convenience of attendants.

The object of my invention is to provide a simple, light, and comparatively inexpensive 20 bed-rest susceptible of a wide range of adjustment, not only for enabling a great variety of positions, but for adapting the rest for use by individuals of all sizes and in beds or on lounges of different lengths.

25 After fully describing the bed-rest illustrated in the drawings, the features deemed novel will be specified in the several claims hereunto annexed.

Referring to the drawings, Figure 1 illustrates in top and edge views the frame-work 30 of one of my rests as when folded and out of use or for transportation. Fig. 2 in similar views illustrates the same with the several main parts distended. Fig. 3 illustrates the 35 same in edge or side view in one of its positions of adjustment on a mattress and bedstead. Figs. 4 and 5 in similar views illustrate other positions of adjustment of the rest on the bed. Fig. 6 in two views illustrates a 40 commode attachment. Fig. 7 in two views illustrates a table attachment. Fig. 8 in side view and central cross-section illustrates a detached friction-bar used on the base of the bed-rest.

45 It is to be understood that my bed-rest is so upholstered as to afford comfort to its user, and that the character of the upholstering can be indefinitely varied without in any manner affecting my invention.

50 The frame-work or skeleton of a bed-rest embodying my invention essentially includes a central or base section, A, an auxiliary base-

section, B, and a back-supporting section, C, all hinged together longitudinally, and so that the auxiliary base-section and the back-supporting section will fold toward and upon each other over or upon the base-section. The base-section A performs no other function than that of a base for the other sections, and it is composed of a pair of bars, *a*, and provided with 55 a downwardly-curved and projecting cross-bar, *b*, which I will term a "friction-bar," because its function is to seat itself so firmly into a mattress as to prevent any undue slipping action thereon.

65 Bed-rests as heretofore constructed have embodied cross-bars operating as ties or braces for coupling the side bars of the frame-work, and said cross-bars of necessity served to hold the device more firmly on a bed than would 70 be the case if they were not used. My friction-bar, being downwardly curved and projected materially below the plane occupied by the side bars of the framing, is effectually embedded in a bed or mattress, instead of merely 75 resting thereon, as would be the case if said bar, like said prior cross-bars, occupied substantially the same plane as the side bars. This transverse friction-bar is preferably composed of metal, and has one or two sharp or 80 well-defined edges, which enable it to properly engage with a sheet or mattress without liability of injury thereto, as distinguished from the use of card-teeth, as heretofore proposed for a like purpose. The auxiliary base-section 85 B is not only at times an actual prolongation of the base A, but it also serves as a means for the longitudinal adjustment of the base upon a bed, and when so serving it also serves as a portion of the means by which the 90 inclination of the back-supporting section can be adjusted; and, still further, it serves at times as the sole means for adjusting said back-section.

95 As essential features in construction, the auxiliary base at its outer end is provided with one or more beveled faces, *c*, and a notched rack-bar, *d*. Otherwise it may be variously constructed, although, as hereshown, it embodies two side bars, *e*, and two cross-bars, *e'*.

100 The back-supporting section C embodies two side bars, *f*, which at their rear sides are notched to serve as rack-bars, a curved cross-

bar, f' , near its hinged end, and a lateral or cross bar, g , at its outer end. It is essentially provided with a brace, h , hinged at its rear side and near its outer end, and for economy 5 and lightness I have attached this brace rigidly to the cross-bar g and hinged this latter to the side bars, f . The brace h , at its outer end, is beveled, so as to enable it to engage with the notches of the rack-bar d on the auxiliary 10 base-section.

Referring now to Fig. 3, it will be assumed that an invalid wishes to sit nearly upright and as near the head of the bed i as possible. In this case the auxiliary base B serves purely 15 as a brace, its beveled faces occupying such of the notches f^2 at the rear of the side bars, f , of the section C as will afford the desired inclination for the invalid. The auxiliary base-section, at its junction with the base-section, 20 is in abutting contact with the head-board, and therefore a firm, unyielding support for the invalid is afforded. The upholstering between the side bars, f , enables the body to cushion itself comfortably, there 25 being no cross-bars except the two mentioned, and one of these is above the position occupied by the head of the invalid, and the other bar, f' , is curved so far rearwardly as to afford no discomfort. When thus adjusted, the brace 30 h overlies, or it may underlie, the auxiliary section, and is out of service.

Referring now to Fig. 4, it will be assumed that an invalid wishes to be in a slightly-inclined position and well down in the bed i . 35 In this case the base, and also the auxiliary base-section, lies flatly on the mattress, and the brace h , at its outer end, engages with the rack-bar d at the notch nearest its outer end. When thus arranged, the invalid is firmly 40 supported. His feet may be pressed against a foot-board, if desired, and various inclinations can obviously be provided for by varying the position of the brace h on the rack-bar.

Referring now to Fig. 5, it will be assumed 45 that the wishes of the invalid, or his condition as to size and weight, render it desirable that the back-section C be located at some point on the bed between the two extreme positions of adjustment therein already described. As here shown, the auxiliary base 50 is inclined, and at its outer or upper end it lies against the head-board of the bedstead, thus obviously enabling the base-section to be located at various points in the bed, according 55 to the degree of inclination of the auxiliary base. The brace h , by its varied engagement with the notches of the now inclined rack-bar d , enables a corresponding variation in the inclination of the back-supporting section.

60 It is not deemed necessary to specially indicate the various circumstances under which these several capacities for adjustment will be found of value, as it is believed that they will be readily appreciated by invalids and experienced nurses.

The importance of a commode attachment

to a bed-rest will be obvious, and I have provided a commode, D , so constructed that it can be readily coupled to the back-section near the base, as indicated in dotted lines in Fig. 5, by means of the spring-arms k , having inwardly-bent ends, as shown in Fig. 6, thus forming hooks, so that by springing said arms apart they will embrace the two side bars and engage therewith sufficiently to hold the commode from slipping forward. It is to be understood that these hooks are mere coupling devices, and that any other well-known forms of coupling straps and hooks can be employed so long as the commode is thereby prevented 70 from sliding away from its proper position and unduly tilting. The pendent front end, l , of the commode is nearly the height of an ordinary vessel, so that the latter will be pressed into the mattress and firmly held thereon by the weight of the invalid, but without liability of being upset or unduly subjected to pressure.

For enabling the commode to occupy minimum space when not in use, the pendent front 80 l may be hinged so as to fold backward, and be also provided with a hook or bolt for firmly securing it in position for service without departure from my invention. In some cases I also provide the commode with a pendent rear 85 end, as indicated in dotted lines.

The desirability of a firm, reliable, and readily-applied table or book-stand to a bed-rest will be obvious, and I have devised the table E , (shown in Fig. 7,) which embodies a frame 90 composed of a light flat bar, m , preferably of iron, and a similar bar, m' , at right angles thereto, and a light board, n , thinner than the width of said bars, and secured thereto centrally, so that said bars at their two edges 95 serve as lips or ledges for the two faces or sides of the table-board. The side bar, m , near its foot, has a lateral hole, m^2 . At one or both edges of the auxiliary base-section, 100 near its hinged joint, there are hooks o , and similarly located on the back-section there 105 are rectangular hooks, serving as brackets p . The table is placed in position for use by engaging one of the hooks o by the side bar, m , at its hole m^2 , and locating the bar in one of 110 the brackets p , as clearly indicated in dotted lines in Fig. 3. As thus constructed the table 115 can be applied and used at either side of the bed-rest and either side up, and in either case there will be free and unobstructed space 120 at one side of the table, thus obviating the sense of constraint generally so objectionable to invalids.

My rests can be cheaply constructed, and yet be light, strong, and serviceable, as will 125 be obvious when I state that for ordinary service they need weigh but about six or seven pounds.

Having thus described my invention, I claim as new and desire to secure by Letters Patent— 130

1. In a portable bed-rest, the combination, substantially as hereinbefore described, of the

base-section, the auxiliary base-section provided with a rack-bar and hinged to the base-section, and the back-section, also hinged to said base-section, and provided with a hinged brace for engaging with the rack-bar on the auxiliary base-section.

2. The combination of the base-section, the auxiliary base section hinged thereto and provided at its outer end with beveled tips, and the back-section hinged to said base-section and provided with notches at its rear side, substantially as described, whereby said auxiliary base may operate as a direct adjustable brace for the back-section.

15 3. The combination of the base-section, the auxiliary base-section hinged to said base-section, and provided with a rack-bar and beveled tips, and the back-section provided with notches at its back, and also with a hinged
20 brace, substantially as described, whereby said back-section may be rigidly and firmly ad-

justed at various inclinations and in various locations on a bed, as set forth.

4. The combination, with the three bed-rest sections, of the table provided with a bar 25 adapted to engage with the edges of the auxiliary base and the back section, and thus be mounted for service, substantially as described.

5. The combination, with the bed-rest, of the commode provided with coupling-hooks 30 for detachably connecting it with the back-section near its base, and projecting forwardly therefrom and having a pendent front end, substantially as described.

6. The combination, with a bed-rest base-section, of the downwardly-curved transverse sharp-edged friction-bar, substantially as described, and for the purposes specified.
